EX

OR D 14,317

Design No. 14,317, dated September 18, 1883.

UNITED STATES PATENT OFFICE.

JOSEPH F. REITZ, OF EVANSVILLE, INDIANA.

DESIGN FOR A BUREAU.

SPECIFICATION forming part of Design No. 14,317, dated September 18, 1883.

Application filed May 18, 1883. Term of patent 7 years.

To all whom it may concern:

Be it known that I, JOSEPH F. REITZ, of Evansville, in the county of Vanderburg and State of Indiana, have originated and invented 5 a new and useful Design for Bureaus; and I do hereby declare that the following is a full, clear, and exact description thereof, reference being had to the accompanying photograph, forming a part of this specification.

10 The photograph represents a bureau embodying my improved design, the feature of which consists in forming the drawers with a taper or beveled front, A, also a similar bevel or taper, B, for the casing, thus giving a neat, 15 finished, and ornamental appearance to the article of furniture.

I claim as my invention—

A design for bureaus or other like articles of furniture, having its drawer or drawers formed with a bevel or taper front, A, and the 20 casing or casings thereof with a similar bevel or taper front, B, substantially as shown.

In testimony that I claim the foregoing as my own I affix my signature in presence of two witnesses.

JOSEPH F. REITZ.
